UNITED STATES PATENT OFFICE.

ANDREW J. JOHNSON, OF GREEN BAY, WISCONSIN.

LANTERN.

1,309,893.

Specification of Letters Patent.

Patented July 15, 1919.

Application filed May 7, 1918. Serial No. 233,123.

To all whom it may concern:

Be it known that I, ANDREW J. JOHNSON, a citizen of the United States, residing at Green Bay, in the county of Brown and

5 State of Wisconsin, have invented certain new and useful Improvements in Lanterns, of which the following is a specification.

This invention relates to lanterns, and more particularly to safety lanterns for use 10 on Christmas trees.

The object of the invention is to provide a simply constructed, cheap light of this character which, while being absolutely safe will yet diffuse a maximum quantity of light of 15 any color desired.

Another object of the invention is to provide a simply constructed, cheap light of this character, in which the light producing medium may be quickly and easily removed 20 and replaced.

Another object is to provide means capable of performing the double function of a suspension device and a deflector holder.

With the foregoing and other objects in 25 view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figure 1 represents a side elevation of a lantern constructed in accordance with this invention,

Fig. 2 is a longitudinal section taken on the line 2—2 of Fig. 1, and

40 Fig. 3 is a top plan view thereof.

The lantern constituting this invention, which is especially designed for use as a Christmas tree light, comprises a tubular member 1 preferably cylindrical in form, 45 although not necessarily so, and which is composed of mica or other suitable transparent, non-frangible material, and which may be colored to suit the user.

This cylinder 1 is arranged on a sleeve 2 50 composed of thin tin, aluminum, or other suitable metal, the lower end of the cylinder being shown arranged abutting the upper end of the sleeve, and it is connected thereto by means of a bail or U-shaped brace member 10, the arms 11 and 12 of which straddle the cylinder and are secured thereto and

to said sleeve at diametrically opposite points by rivets, the free ends of these arms terminating flush with the lower edge of the sleeve.

60 This sleeve 2 has a bayonet slot 3 opening inwardly from its lower edge as is shown clearly in Fig. 1, and which is designed to receive a headed stud 4 which projects laterally from one side wall of a base or candle carrying member 5. This member 5 is made cup-shaped and has a socket 6 flared to receive a candle C. It will thus be seen that the candle carrying member 5 may be readily inserted or detached by exerting a slight 65 twist thereon toward the right or the left to connect or disconnect the bayonet slot 3 with the head of the stud 4.

70 As shown, the candle carrying member has a flared base 7 and is provided with an annular shoulder 8 on which the lower end of the sleeve 2 rests as is shown clearly in Fig. 2.

75 A top or deflector 9 is supported above the upper of the cylinder 1 and projects laterally beyond the side walls thereof, being designed to deflect the products of combustion as they rise from the candle to prevent burning of objects disposed above the candle. 80 This top 9 is here shown in the form of a transparent disk having recesses 9' disposed at diametrically opposite points in its periphery, which are designed to receive the arms 11 and 12 of the combined brace and suspension member 10. The cross bar 13 of 85 the bail shaped member extends above the disk 9 and is connected therewith by a suspension element in the form of an eye bolt 14. The eye 15 of this bolt is designed to receive a fine wire or other means for attaching the lantern to a branch of a Christmas 90 tree or to any other suitable support.

95 While the light producing medium is here shown and described as a candle, it is of course to be understood that a lamp may be used as a substitute for the candle without departing from the scope of this invention.

100 The foregoing description and the drawings have reference to what may be considered the preferred or approved form of my invention. It is to be understood that I may make such changes in construction and arrangement and combination of parts, materials, dimensions, *et al.*, as may prove expedient and fall within the scope of the 105 claimed invention.

110 Having thus fully described my invention,

what I claim as new and desire to secure by Letters Patent, is:—

A lantern of the class described comprising a tubular body member of transparent non-frangible material, a thin metal sleeve arranged flush with the lower end of said member with their adjacent ends abutting, an inverted U-shaped brace composed of a strip of flat metal with its legs straddling 10. said sleeve and member and riveted thereto, said sleeve having a bayonet slot in its lower edge, a cup-shaped member with a centrally disposed socket and a flared base with an annular shoulder at the juncture of its base 15 on which said sleeve rests, said cup-shaped member having a laterally projecting headed

stud for detachable connection with the slot in said sleeve, a disk-shaped deflector having diametrically opposite recesses to receive the arms of said brace, the periphery of said deflector extending laterally beyond the side walls of the body member, and a suspension element in the form of an eye bolt extending through said curved brace portion and deflector, the eye portion projecting outwardly 25 to form a suspension device.

In testimony whereof I affix my signature in presence of two witnesses.

ANDREW J. JOHNSON.
